UNITED STATES PATENT OFFICE.

JOHN F. FARRINGTON, OF NEW YORK, N. Y., ASSIGNOR TO WESTERN ELECTRIC COMPANY, INCORPORATED, OF NEW YORK, N. Y., A CORPORATION OF NEW YORK.

DUPLEX TRANSMISSION SYSTEM.

Application filed December 24, 1920. Serial No. 432,900.

This invention relates to duplex transmitting methods and systems and more particularly to methods of and apparatus for duplex radio transmission for simultaneous 5 telephony and telegraphy.

An object of the invention is to provide a plurality of simultaneous signal transmission channels with a single carrier oscillation source.

10 Another object is to provide means whereby an operator at a called radio station may "break in" on the operator at the calling station.

15 A feature of the invention is the provision of a duplex high frequency signaling system serving for simultaneous telephony and telegraphy and having means for stepping down the received high frequency waves to an intermediate inaudible frequency. This 20 enables greater amplification and selectivity to be had.

25 An additional feature of the invention is the provision of means for discriminating between and selectively indicating amplitude modulations of a carrier wave such as are produced in ordinary carrier wave telephony and prolonged constant frequency changes in the carrier frequency itself such as may be used to transmit code signals.

30 Further objects of the invention will be apparent upon consideration of the detailed description and claims.

According to this invention a signaling station is provided with a source of oscillations which serve the double function of carrier waves for an outgoing transmission and reinforcing or intermediate frequency producing oscillations for the received waves of an incoming transmission. The outgoing carrier waves may be modulated in any desired manner for one transmission. The frequency of the outgoing carrier waves may be varied in accordance with a code for a second transmission. The two transmissions 40 may therefore be simultaneous. At the distant station the modulated waves of the first transmission are combined with locally generated reinforcing oscillations to produce inaudible intermediate frequency modulated oscillations which may be selected and detected. The changed frequency carrier waves are combined at the distant station with the locally generated reinforcing oscillations to produce changed intermediate frequency oscillations. The changed intermediate fre-

quency oscillations are combined with locally generated oscillations to give in a second receiving circuit a beat note. The two stations which communicate with each other are similarly equipped the principal difference being due to the fact that their principal carrier oscillation sources generate oscillations which differ in frequency by the normal intermediate frequency.

In the drawing, Fig. 1 illustrates a duplex radio transmitting and receiving station equipped for simultaneous telephony and telegraphy; Fig. 2 a similar system having a modified modulator and Fig. 3 illustrates a modification in certain details of the receiver at the right of line $a-a$ in Figs. 1 and 2.

Referring to Fig. 1, a constant current modulating system 1, having an oscillator of well known type, comprising three-element tube 2 and its associated circuits, is shown arranged for radio telephone transmission. (See Fig. 16 page 360 Proc. A. I. E. E. March 1919.) The antenna is broadly tuned to the frequency f_1 of the oscillations produced by source 2 and therefore serves to transmit oscillations of frequencies $f_1 + s_1$ and f_1 representing respectively the side bands and the unmodulated carrier component of speech modulated outgoing carrier waves. The frequency of the speech waves at this station is represented by s_1 . In order to change the carrier frequency f_1 for code signaling, a key 6 is provided to short circuit a reactance in the frequency determining circuit of the oscillator. For explanation purposes the reactance is of such character that closing the key 6 will decrease the carrier frequency. The distant communicating station, not shown, has similar transmitting apparatus except that its oscillator produces waves of frequency f_2 and accordingly transmits to the station of Fig. 1, oscillations of frequencies $f_2 \pm s_2$ and f_2 representing, respectively, the modulated side bands and unmodulated carrier frequency component, s_2 denoting the frequency of speech waves to be transmitted from the distant station. In order to efficiently select and receive the incoming waves, the antenna of Fig. 1 is provided with an additional path 3 tuned in conjunction with the transmitting antenna circuit to the mean frequency of the received waves. This path includes a loop 4 antiresonant at the fre-

quency f_1 and accordingly has substantially no effect on outgoing transmission at that carrier frequency. A slight amount of the energy for the outgoing transmission finds its way over this path and is applied with the received waves to the input circuit of a detector D to give in the output circuit, among other components, one of the inaudible difference frequency of the two carrier waves. During outgoing speech transmission this inaudible difference or intermediate frequency component is modulated by waves of frequency s_1 and during incoming speech transmission by waves of frequency s_2 , as will be apparent by considering the frequencies of the waves combined. A loop 5 or appropriate band filter adjusted to the normal intermediate frequency $f_1 - f_2$ but capable of transmitting the speech modulated intermediate frequency side bands and a similarly selective coupled input circuit of detector D_1 selects the intermediate frequency component for detection by detector D_1 to give in the associated receiver currents of speech frequency s_1 or s_2 as the case may be. A loop 7 and a coupled input circuit of a detector D_2 are both tuned to the changed intermediate frequency obtained when the operator at the distant station closes his key 6 to change the frequency f_2 of his outgoing carrier oscillations. Coupled to the input circuit of detector D_2 is a source G_2 of oscillations of the normal intermediate frequency $f_1 - f_2$. The detector D_2 accordingly supplies to receiver R associated therewith, a wave of the difference frequency of the normal and changed intermediate frequency waves. This wave, the frequency of which is determined by the amount of change in the carrier frequency f_2 , is preferably below the essential speech frequency range. A filter FL may therefore pass this wave and extinguish speech currents of frequencies s_1 and s_2 transmitted thru or produced at detector D_2 . The change in incoming carrier frequency and consequently in the intermediate frequency will not seriously affect transmission of the speech modulated waves to detector D_1 . Telephony is therefore independent of telegraphy. Since the normal intermediate frequency oscillations produce no continuous low frequency beat note with oscillations from the source G , and the low pass filter excludes waves of all higher frequencies than this note, the receiver R will normally give no response. The tendency to transmit speech currents to receiver R as a consequence of the combination at detector D_2 of speech modulated intermediate frequency oscillations and reinforcing oscillations of the intermediate frequency, is eliminated by filter FL which suppresses currents of the essential speech frequencies. The operation at both stations is the same, due regard being had for the difference in the nor-

mally transmitted carrier wave frequencies. The receivers at each station indicate not only incoming signals but also outgoing signals since transmissions in either direction act alike on these receivers. The telephone transmission may of course be interrupted in the ordinary manner by the operator at the called station. The telegraph transmission may be interrupted at will by the receiving operator by the simple expedient of closing his key 6 thus changing the frequency of his continuously outgoing carrier wave by the same extent that the transmitting station operator changes his own carrier wave frequency for transmission of telegraph signals. There will accordingly be no beat note when the transmitting operator closes his key but the note will reappear when he opens it. This notifies him that the receiving operator is trying to "break in".

In Fig. 2 the oscillator and its associated key 6 are related as in Fig. 1. The oscillator instead of supplying modulated oscillations to an antenna is connected to supply unmodulated oscillations to an arrangement of two thermionic amplifiers in tandem. The second of these amplifiers, HA , transmits the amplified oscillations to the antenna and is provided, together with a speech controlled modulating tube M , with a constant space current source, to enable modulation of the oscillations by amplifier HA . This constant current source consists merely of the ordinary space current source in series with a large speech frequency retard or choke coil. The operation of this modulating arrangement is identical in principle with that of Fig. 1, except that modulation takes place at amplifier HA instead of at the oscillator.

In a system of the present type in which incoming and outgoing carrier waves are combined, it is desirable that the carrier frequency should not be changed during the process of modulation; that is, the operation of the speech circuits in effecting modulation should not change the carrier frequency but should merely introduce speech side bands based upon a constant frequency carrier wave. A characteristic feature of the present system is its ability to do this because the carrier frequency is set or established by the oscillator O which is not affected by impedance changes of the amplifier HA in the process of modulation. It is especially desirable that such rapid changes of carrier frequency should not occur in a system in which small carrier wave frequency changes are employed to effect telegraphic communication as the undesired changes might be of the same order of magnitude as the telegraphic changes and cause an interference.

Consequently, the telephone communication may be regarded as occurring on a fixed

wave length during periods between telegraphic wave length changes and, of course, on the same invariable wave length at all times when the telegraph portion of the system is not working or between telegraph messages. The frequency changes referred to above are those which occur with considerable rapidity during the process of modulation (in some systems) and are entirely independent of the much more slowly occurring telegraph changes.

In the modification of Fig. 3, the generator G is designed to produce oscillations not of the normal intermediate frequency but differing therefrom by a frequency considerably exceeding the highest essential speech frequency as, for example, by 5000 cycles. The frequency of oscillator G may therefore be either $f_1 - f_2 + 5000$ or $f_1 - f_2 - 5000$. Detector D_2 will yield in its output circuit oscillations of the difference frequency produced by combining waves from source G and incoming changed intermediate frequency waves representing telegraph signals. If the latter are of frequency $f_1 - (f_2 - 150)$, as it would be in the case assumed, the output circuit of detector D_2 will yield waves of frequency 5000 ± 150 depending upon which of the two frequencies $f_1 - f_2 + 5000$ or $f_1 - f_2 - 5000$ is used for generator G. Band filter FB will accordingly be designed to transmit waves of either 4850 or 5150 cycles to detector D_3 and to exclude currents of speech frequencies and of the 5000 cycle modulated and unmodulated currents which are produced by combination of normal intermediate frequency speech modulated waves and oscillations from source G. The waves transmitted by filter FB are combined at detector D_3 with oscillations from a source G_1 , of frequency outside the transmission range of the filter, to produce an audible note preferably low in comparison with essential speech frequencies. To the extent that filter FB does not exclude speech modulated 5000 cycle currents, these will give rise at detector D_3 to speech currents and also to audible noise currents resulting from the combination with oscillations from source G_1 . Filter FL_2 designed to pass the low frequency audible telegraph note excludes currents of the essential speech frequencies and substantially all of the noise current energy.

Should oscillations be transmitted from generator G thru circuits 7 and 5 to detector D_1 , these oscillations, if of normal intermediate frequency, might combine at detector D_1 with speech modulated changed intermediate frequency oscillations to give the difference frequency currents representing, not speech, but speech currents modulated by the low frequency telegraph wave and hence might produce an unintelligible indication in the telephone receiver. If for

example the incoming carrier wave frequency were changed for telegraphy by 150 cycles it would be represented by $f_2 - 150$ and the changed intermediate frequency wave as modulated by speech would be represented by $f_1 - (f_2 - 150) \pm s_2$ which combined with the normal intermediate wave of frequency $f_1 - f_2$ would result in the unintelligible waves of frequencies $150 + s_2$ and $150 - s_2$. By changing the frequency of the local source G to $(f_1 - f_2) \pm 5000$ these unintelligible components become $5150 \pm s_2$ or $4850 \pm s_2$ and hence may be readily separated from the speech currents of frequency s_2 by filter FL_1 which passes currents of essential speech frequencies and substantially extinguishes currents of higher frequencies.

It should be understood that the invention is not to be limited to radio transmission nor to the systems, circuit details or sequence of operations disclosed but only by the scope of the appended claims.

What is claimed is:

1. The method of high frequency signaling comprising transmitting and receiving a carrier wave, producing an inaudible difference frequency wave by combining with the received carrier wave a second carrier wave having another frequency, changing the carrier frequency of said first named carrier wave by an audible amount in accordance with signals and thereby producing a corresponding change in said difference frequency wave, and producing from said difference frequency wave an audible frequency wave whose frequency varies in accordance with the change in said difference frequency wave.

2. The method of high frequency signaling comprising transmitting and receiving a carrier wave, producing a wave of different frequency, combining said waves to produce a beat frequency wave, changing the frequency of said carrier wave to transmit signals, and thereby producing a corresponding change in said beat frequency and producing with said beat frequency wave a wave whose frequency equals said change.

3. In a system for carrier wave transmission in which signals are transmitted by modulating a high frequency carrier wave in accordance with modulation frequency impulses and by changing the normal carrier frequency, the method of reception which comprises detecting the modulation component of the carrier wave and detecting the changes in the normal carrier frequency by causing a wave derived from the carrier wave to continuously coact with a locally produced wave to produce beats.

4. In the method of simultaneous telephony and telegraphy in which telephonic signals are transmitted as modulations of a carrier frequency wave, and in which telegraphic signals are transmitted by changing

the carrier frequency of said wave by an audible amount, the method of reception which comprises detecting the telephonic signals by demodulating a portion of the received energy, and receiving the telegraphic signals by combining a portion of the received wave with a locally produced wave, the frequency of which differs from the normal carrier by an inaudible amount, detecting said combined waves, selecting from the detected wave the frequency component corresponding to the difference between the carrier and local frequencies, and stepping down said difference frequency to the value corresponding to the change in the carrier frequency.

5. The method of two-way signaling which comprises continuously transmitting in opposite directions between two communicating stations two high frequency waves differing by an inaudible frequency, combining at each station the received wave with a portion of the transmitted wave from the same station to give an auxiliary difference frequency wave, changing the frequency of the transmitted wave at either station by an audible amount in accordance with a signal, and detecting said signal at the other station by combining with the changed auxiliary frequency wave resulting from said signaling operation a wave having a frequency equal to the auxiliary frequency during non-signaling operation, and separating from the product of the combining operation the audible frequency component which is present when signals are being transmitted from the distant station.

6. A method of simultaneous modulated carrier wave and high frequency signaling which comprises continuously transmitting from two communicating stations high frequency carrier waves differing from each other by an amount above good audibility, modulating either one of said waves in accordance with a low frequency wave simultaneously with the modulation changing the frequency of either of said carrier waves in accordance with a signal, combining at each station the normally received wave with a portion of the transmitted wave to give a modulated intermediate frequency carrier wave, detecting a portion of said intermediate frequency wave to reproduce the modulating wave, and combining with another portion of said intermediate frequency wave, a wave from a local source to give a resultant audible beat note when either of the carrier frequencies is changed.

7. A carrier wave transmission system including a source of carrier waves, means for changing the frequency of said waves to transmit low frequency impulses, a receiving station having a local source adapted to generate waves whose frequency differs at every instant from that of said carrier wave,

detecting means responsive to the simultaneous action of said waves and the waves from said local source to produce a difference frequency wave whose frequency changes in proportion to the change in frequency of said carrier wave, and detecting means for producing from said difference frequency wave a wave whose frequency equals said change.

8. In a transmission system including a modulated carrier wave channel and an additional high frequency wave transmission channel which utilizes the same carrier wave, means for changing the carrier frequency in order to transmit signals, and receiving means including a local source adapted to produce current whose frequency differs at every instant by an inaudible amount from said carrier frequency, means for combining the carrier frequency and the frequency from said source to produce a difference frequency wave, and means for detecting the change of frequency of said difference frequency wave.

9. In a carrier wave transmission system, including transmitting and receiving circuits, means at the former for generating and transmitting a modulated carrier wave, and at the latter, for detecting said wave, additional means at the transmitter for changing the carrier frequency by an audible amount, and circuit means at the receiving circuit responsive to waves set up as the result of changes in said carrier frequency by said audible amount.

10. A carrier wave transmission system comprising, in combination, means for generating and transmitting a modulated carrier wave, means for changing the carrier frequency, a receiving conductor, a local receiver source generating a wave which differs by an inaudible amount from said carrier frequency, detecting means responsive to said carrier wave and the wave from said local source to produce a difference frequency wave, detecting means for producing the modulating component from said difference frequency wave, and means for deriving from the difference frequency wave an audible frequency current when the transmitted carrier frequency is changed.

11. A carrier wave transmission system comprising, in combination, means for generating and transmitting a modulated carrier wave, means for changing the carrier frequency by an audible amount in accordance with a signal, a receiving conductor, detecting means associated therewith, a beat frequency detecting circuit also associated with said receiving conductor, said detecting circuit including means for giving a resultant beat note current having a frequency equivalent to the change in said carrier frequency and including means for preventing the beat frequency current from affecting said first mentioned detecting means.

12. A carrier wave transmission system comprising, in combination, means for transmitting a modulated carrier wave, means for changing the carrier frequency, a receiving circuit, detecting means associated therewith, a local source also associated with said receiving conductor and adjusted to generate a current differing in frequency from the normal carrier frequency by an inaudible amount, a combining device related to said local source and receiving circuit, means in the output circuit of said device selective to the difference frequency of said carrier and local source, a frequency changing means included in circuit with said selective means for decreasing said difference frequency to the value corresponding to the change in carrier frequency, and an indicating means.

13. A two-way signal transmission system comprising two communicating stations each of which comprises, in combination, a source of high frequency waves, means for changing said frequency, a transmitting circuit resonant to said frequency, a receiving circuit resonant to a frequency differing from said first mentioned frequency by an inaudible amount, means for combining a portion of the transmitted energy with energy received from the other station to produce an intermediate frequency wave, a second source of high frequency waves related to said combining means, and additional means related to said combining means and said second source and adapted to derive from the currents associated therewith, an audible frequency current during the intervals of changed carrier frequency.

14. A two-way radio signal transmission system comprising two communicating stations each of which comprises, in combination, a source of high frequency waves, means for changing said frequency by an audible amount, a transmitting circuit resonant to said frequency, a receiving circuit resonant to a frequency differing from said first mentioned frequency by an inaudible amount, means for combining a portion of the transmitted energy with received energy to produce an intermediate frequency wave, a second wave source having a frequency of generation equal to the normal intermediate frequency, combining means for the intermediate frequency waves and the waves from said second source, and means to indicate the resultant difference frequency component when the frequency of the wave received from the other transmitting station is changed.

15. A two-way carrier wave transmission system comprising two stations each of which comprises, in combination, means for generating and transmitting a modulated carrier wave, means for changing the carrier frequency by an audible amount in accordance with a signal, a receiving circuit res-

onant to a frequency differing by an inaudible amount from the transmitting frequency, detecting means for combining a portion of the transmitted energy with the received energy to produce an auxiliary frequency modulated wave, a second detecting means associated with the output of said detecting means, a second source related to the output circuit of said first mentioned detector, and additional means related to said output circuit and said second source for deriving from the currents associated therewith an audible beat note when the carrier frequency is changed at the distant

16. A signaling system comprising an antenna circuit, a transmitting circuit connected to said circuit, said antenna circuit being resonant at the frequency of waves to be transmitted, a circuit in shunt to said antenna circuit, reactance means in said shunt circuit for tuning said antenna and shunt circuits together to resonance with the frequency of waves to be received, a receiver circuit coupled with said shunt circuit, reactance means in said shunt circuit whereby the impedance of said shunt circuit does not substantially affect the tuning of the system as a whole for the transmitted frequency, said means permitting a relatively small portion of energy of the transmitted frequency to be received in said receiver circuit, and means for combining in said receiver circuit the energy of the normally received wave and said portion of the energy of the transmitted frequency which is received therein.

17. The method of radio signaling between two communicating stations, which consists in continuously transmitting a carrier wave from each station, varying the frequency of the carrier wave from one station in accordance with signals, beating the received wave at the other station with a portion of the wave normally transmitted from said other station to produce a variable intermediate frequency wave, detecting said intermediate frequency wave to produce an audible frequency wave having signal frequency variations, and breaking-in on said signal transmission by simultaneously varying the frequency of the wave transmitted from the other station.

18. The method of claim 17 in which the variations in the carrier frequencies from the two stations are equal and in the same direction with respect to the normal frequency.

19. The method of two-way radio telephony and telegraphy between two stations which consists in continuously transmitting a carrier frequency wave from each station, receiving said carrier wave at the other station, combining at each station a portion of the transmitted wave with the received wave, to produce an intermediate

- frequency wave, modulating the carrier frequency from one station in accordance with voice signals, detecting the intermediate frequency wave to reproduce the voice signals at the receiver, simultaneously transmitting a telegraph signal over the same carrier wave, and breaking-in on said telegraph signal transmission by modifying the carrier wave at the receiver.
- 10 20. A system of radio communication between two stations which comprises means at each station for transmitting a carrier wave, means for varying the frequency of the carrier wave from one station in accordance with signals, means for beating the received wave at the other station with a portion of the wave normally transmitted from said other station to produce a variable intermediate frequency wave, means for detecting said intermediate frequency wave to produce an audible frequency wave having signal frequency variations, and means for breaking-in on said signal transmission by simultaneously varying the frequency from said other station by the same amount and in the same direction as the variation at said transmitting station.
- 15 21. A two-way radio telephone and telegraph system comprising means for continuously transmitting a carrier frequency wave from each of two communicating stations, means for receiving said waves at the communicating stations, means for combining at each station a portion of the normally transmitted wave with the normally received wave to produce an intermediate frequency wave, means for modulating the carrier wave from one station in accordance with a voice signal wave, means for detecting the intermediate frequency wave to reproduce the voice signal wave at the other station, means for simultaneously transmitting a telegraph signal over the same carrier wave used for voice signaling, and means whereby a receiving operator can break in on said telegraph transmission.
- 20 22. In a radio signaling station the combination of an aerial capacity and two branches connecting it to earth, means for generating and impressing upon one of said branches waves of a frequency to be transmitted, means in the other of said branches for rendering said other branch of high impedance to the generated waves, means in one branch for tuning said aerial capacity to form a resonant combination for the impressed waves, means in said other branch for tuning said aerial capacity and said branches as a whole for currents of a frequency to be received whereby said branches and said aerial have a resonance peak at the frequency of waves to be received, and a receiving circuit coupled to said other branch including means for combining energy of said impressed and received waves to produce combination frequency waves of frequency above good audibility.
- 25 23. A two-way radio terminal comprising elements for generating high frequency carrier oscillations, an amplifier for amplifying said oscillations, a source of current for supplying said amplifier, means to prevent signaling frequency variations in said current thereby keeping said current constant, a signal controlled variable impedance device in shunt to said amplifier with respect to said source and means, and a transmitting conductor for transmitting the resultant variable amplified waves in combination with means for combining a portion of the energy of the amplified waves with energy of a signal modulated incoming carrier waves to produce a new carrier wave, detecting means for the new carrier wave, and indicating means for the resultant signal wave.
- 30 24. The method of signaling which comprises producing carrier waves of substantially constant frequency, impressing the resultant waves upon the input circuit of an amplifier, supplying current of substantially constant value to the output circuit of said amplifier, variably diverting current away from said amplifier in accordance with signals to be transmitted, transmitting wave energy of the resultant modulated waves, combining a portion of the resultant wave energy with received wave energy to produce an inaudible intermediate frequency carrier wave, and selecting and detecting the inaudible intermediate frequency carrier wave.
- 35 25. A two-way signaling system comprising means for receiving and combining speech modulated energy of an incoming carrier wave with energy of a speech modulated outgoing carrier wave of another frequency in combination with a source of substantially constant frequency oscillations for producing the outgoing carrier wave, and an amplifier having its anode circuit controlled by speech waves to modulate said oscillations.
- 40 26. The method recited in claim 24 comprising the additional steps of simultaneously varying the frequency of said carrier waves in accordance with a second set of signals so that the resultant intermediate frequency carrier wave has a corresponding frequency variation, and operating on said variable frequency intermediate frequency carrier wave so as to independently obtain an audible frequency wave having signal frequency variations corresponding to the second set of signals and to reproduce the first mentioned signals.
- 45 27. In witness whereof, I hereunto subscribe my name this 22nd day of December, A. D., 1920.
- JOHN F. FARRINGTON.
